VAPORIZER CARRIER

Max Katzman, Brooklyn, N. Y.

Application October 25, 1949, Serial No. 123,463

5 Claims. (Cl. 219—40)

1

This invention relates to carriers for vaporizers and has for one of its objects to provide a stable carrier and stand combination for a vaporizer.

Another object is to provide a simple and inexpensive handle for a vaporizer which may be easily and conveniently attached and removed.

Another object is to provide effective means for preventing separation of the vaporizer container and its lid while the electric current is on, in order to protect the user against burns from touching the heating element and against receiving an electrical shock.

A still further object is to provide a protective carrier which will prevent the vaporizer container from cracking or breaking by cushioning the shock when the unit is set down sharply.

A still further object is to provide a vaporizer carrier and stand combination which may be formed as a sheet metal stamping, and which will always rest firmly on a horizontal surface.

Other objects and advantages will hereinafter appear.

In the accompanying drawings in which similar reference characters denote corresponding parts:

Fig. 1 is a front elevation of an illustrative carrier and stand unit in place on a vaporizer;

Fig. 2 is a top view showing the container and handle and;

Fig. 3 is a top view in section, on the line 3—3 of Fig. 1, illustrating the construction of the stand.

Referring to the drawings, the vaporizer unit is generally shown at 10, and is of usual construction, comprising a conventional liquid container 11, which may be a glass jar. Heating electrodes 12 are attached to, but insulated from, the bottom of a cap 13 which is adapted to be screwed onto the top of the container 11. The cap 13 also includes a vapor emission spout 14, and electrode terminals 15 and 16 which project from the lid 13.

The combination carrier and stand which embodies the invention is generally designated at 17. It is constructed principally of resilient sheet metal or other suitable resilient material. It is basically a U-shaped spring clamp formed to provide a lower jaw or bases 18, an upper jaw 19 and a connecting handle member 20.

The upper jaw 19 comprises an inbent upper end of the handle member 20 and a rigid, notched, insulating extension plate 21 secured thereto by rivets 22. The plate 21 is designed to fit around the protruding electrode terminals 15 and 16 and to extend between the cover and an extension cord plug when the latter is applied to the electrode terminals for heating the vaporizer. The handle member 20 is curved outward away from the vaporizer at its upper end to provide a handgrip space between the handle and the

2

vaporizer, but has its lower end curved and sloped inward, with a sloping portion near its lower extremity disposed to engage and bear resiliently against a lower margin of the vaporizer.

5 The base 18 is an inturned, desirably integral, extension of the handle member 20. It forms a three point support for the vaporizer. At the lower end of the handle member 20 the metal extends downward past the bottom of the vaporizer and is curved to U-form to provide a rear foot 23, which connects with a substantially horizontal body portion 24. The body portion 24 is divided to form divergent arms 25 whose outer ends are bent downward and thence curved 15 to U-form to provide forward spaced feet 26. Beyond the feet 26 the arms 25 terminate in upstanding fingers 27 which extend well above the plane of the body portion 24.

The metallic portion of the carrier may be 20 stamped to provide the divergent arms 25 directly. An economy of metal can be realized, however, if a strip of metal is first stamped with the arms in parallel relation and the arms are subsequently spread to the form shown.

25 The carrier is applied to the vaporizer by inserting the electrode terminals 15 and 16 into the notches of the plate 21 with the carrier spring in inclined relation to the vaporizer as illustrated in dot and dash lines in Fig. 1. The handle and vaporizer body are then pressed toward one another to force the carrier into the full line position illustrated in Fig. 1.

With the fingers 27 and the lower extremity 35 of the handle 20 engaging the bottom portion of the vaporizer periphery at substantially equally spaced points, and with the notched extension plate 21 interlocked with the electrode terminals 15 and 16, the carrier cannot be accidentally separated from the vaporizer. The carrier forms a stable support for the vaporizer which serves to support the hot vaporizer at a distance from any surface upon which the carrier is set. The carrier therefore interferes with the direct transmission of heat from the vaporizer to the supporting furniture, and thereby aids in protecting the furniture from damage.

When the handle 20 is grasped in the usual manner to transport the vaporizer and the vaporizer is then set down, there is a natural tendency to set down the unit so that the rearward foot 23 of the carrier touches the supporting surface first. The vaporizer container 11 being generally constructed of glass, is likely to be rather fragile, and the sudden shock created when the unit is carelessly placed on a supporting surface may crack the container 11. To avoid this danger the carrier is so constructed that the base 18 does not normally rest against the bottom of the container 11 in the region of the foot 23.

60 The arms 25 and the body 24 of the base do

not extend in a plane parallel with the plane defined by the lowest points of the three supporting feet 23, 26, 26, but do extend in a plane which slopes downward from the front to the rear. The bottom of the vaporizer container 11 is, however, caused to occupy a substantially horizontal attitude, and hence to diverge rearwardly from the arms 25 and the body 24.

This divergence is brought about by reason of the fact that the normal space between the fingers 21 on the one hand and the lower extremity of the handle 20 on the other is insufficient to accommodate the container 11. The fingers 21 and the handle 20 therefore exert a squeezing action upon the container. The lower extremity of the handle 20 deviates sufficiently from the vertical, and from parallelism with the fingers 21, to cause it to cam the lower rear edge of the container upward. This causes the rear portion of the container to be resiliently supported at a short but important distance from the surface of the body 24. With this construction, the shock applied to the foot 23 when the carrier is set down will not be transmitted as a shock to the container 11, but will be absorbed by the resiliency of the handle 20. This action effectively protects the container against cracking.

When the handle is in place the cap 13 cannot be removed without first removing the handle and stand unit. The user is prevented, therefore, from taking the device apart, thus being prevented from burning himself on the heating electrodes 12. In case an electrical plug, not shown, is seated on the electrode terminals it effectively interferes with the removal of the carrier from the vaporizer, at least until the electrical connections are broken. Since the cover cannot be removed until the carrier has been removed, there is no danger of exposing the electrodes while they are connected to the source of current.

It will now be appreciated that the novel carrier and stand combination will serve to fully realize the several objects hereinabove expressed. The details of present description are to be regarded as illustrative, and not as limiting, inasmuch as numerous variations in structure may be made within the scope of the claims.

I have described what I believe to be the best embodiments of my invention. I do not wish, however, to be confined to the embodiments shown, but what I desire to cover by Letters Patent is set forth in the appended claims.

I claim:

1. A combined carrier and stand, for a vaporizer which includes a container body and a cover with electrode terminals projecting upward from the cover, said carrier comprising an upper jaw engageable with the top of the cover, a lower jaw or base engageable with the bottom of the container body and an intervening handle member resiliently connecting the upper and lower jaws and tending to hold said cover to said container body, said lower jaw and handle member disposed to embrace the lower portion of the container body, and said upper jaw including a notched extension plate which is adapted to be interlocked with the electrode terminals.

2. A combined carrier and stand, for a vaporizer which includes a container body and a cover with electrode terminals projecting upward from the cover, said carrier comprising an upper jaw engageable with the top of the cover, a lower jaw or base engageable with the bottom of the

container body, and an intervening handle member resiliently connecting the upper and lower jaws and biasing them toward one another, said lower jaw being in the form of an extension of the handle member and including a body and a pair of branching arms, said body and each of said arms being curved to form a supporting foot, each of said arms terminating in an upstanding finger, the fingers in cooperation with the handle member being adapted to grip the lower portion of the container body, and the upper jaw including a notched extension plate which is adapted to be interlocked with the electrode terminals.

3. A combined carrier and stand, for a vaporizer which includes a container body and a cover with electrode terminals projecting upward from the cover, said carrier comprising an upper jaw engageable with the top of the cover, a lower jaw or base engageable with the bottom of the container body and an intervening handle member resiliently connecting the upper and lower jaws, said lower jaw being in the form of an extension of the handle member and including a body and a pair of branching arms, said body being curved to provide a rear foot and said arms being curved to provide front feet, each of said arms terminating in an upstanding finger, the fingers in cooperation with the handle member being adapted to grip the lower portion of the container body and to cause the handle member to cam the container upward at the rear away from the lower jaw.

4. A combined carrier and stand for a vaporizer which includes a body and a cover with electrode terminals projecting upward from the cover, said carrier comprising an upper jaw engageable with the top of the cover, a lower jaw or base engageable with the bottom of the container body, and an intervening handle member resiliently connecting the upper and lower jaws and tending to compress said body and cover therebetween, said lower jaw and handle member disposed to embrace the lower portion of the container body, and said upper jaw including a notched rigid extension plate of insulating material which is adapted to be interlocked with the electrode terminals.

5. A combined carrier and stand comprising a lower jaw and an upper jaw and an intervening handle member resiliently connecting the upper and lower jaws and tending to bias said jaws toward one another, said lower jaw being in the form of an extension of a handle member and including a body and a pair of branching arms, said body being curved to provide a rear foot and said arms being curved to provide front feet, each of said arms terminating in an upstanding finger, and said upper jaw including a notched extension plate.
